COLLET WITH AIR CYLINDER OPERATOR

Anton Felin and Louis J. Matthews, Cleveland,
Ohio, assignors, by mesne assignments, to Borg-
Warner Corporation, Chicago, Ill., a corpora-
tion of Illinois

Application November 6, 1944, Serial No. 562,225

3 Claims. (Cl. 90—1)

1

This invention relates to metal working machines generally and particularly to work holding arrangements for such machines wherein the work must be indexed arcuately as well as moved laterally and wherein it is desirable to employ power for the operation of the work holding means.

It is an object of this invention to provide in a machine of the present type a special arrangement for connecting the power unit or motor with the work gripping and releasing arrangement to effect the requisite flexibility and desired efficiency of operation.

It is a more specific object to provide in a connecting arrangement of the above type for both the arcuate indexing of the work holder and for limited longitudinal alignment between the motor and the work holder.

It is a still more detailed object to provide in an arrangement of the present type for the thrust reaction incident to releasing the work from the holder to be taken by a stop on the main frame of the machine while normally maintaining free clearance between the reaction points so as not to interfere with the guided relationship between the work holding assembly and the main frame during lateral guided reciprocation of the work in connection with the successive indexing thereof. Likewise it is an object to provide an arrangement wherein the thrust incident to the work gripping operation is taken entirely by the connecting means and no part thereof is transmitted to the frame or lateral guide.

Other and more particular objects, advantages and uses of the present invention will be apparent from a reading of the following specification taken in connection with the accompanying drawing which forms a part thereof and wherein:

The single figure comprises an elevation in section of a gear cutting and shaping machine embodying by way of example one preferred form of the present invention.

The gear cutting and shaping machine, the essential parts only of which are shown, is indicated generally at 10 and preferably comprises the main machine body 11 having supported thereon a collet and adapter assembly indicated generally at 12 arranged both for lateral reciprocation and arcuate adjustment as will appear, this collet assembly being power operated by means of fluid pressure responsive motor 13 connected in a special manner with collet assembly 12 through the medium of flexible coupling made up of portions 14, 16.

It is to this novel arrangement of connecting

2

and supporting means indicated generally at 14 and 16 between the motor 13 and the collet assembly 12 that the present invention is particularly directed.

It will appear that this flexible connecting means is essential since the motor 13 must be restrained against arcuate turning movement while the collet assembly must be indexed arcuately and also reciprocated laterally while at the same time supporting the motor 13 therebelow.

Flexible coupling portion 14 comprises threaded draw bolt 20 terminating at its lower end in a ball 21 cooperating with a socket 22 in the upper portion of tubular connector 23. Partition plate 24 is formed with a coaxial orifice 26 functioning to center and guide tubular socket 23. The outer periphery of partition plate 24 is confined within the lower portion of bell housing 27 having an important function in connection with opening and closing the collet assembly 12 as will appear.

The lower coupling portion 16 includes an adapter 28 having a first threaded portion received in the internally threaded portion of sleeve 23 and a second larger externally threaded portion supporting tubular cage 29 which in turn carries in the lower portion thereof a roller bearing raceway or plate 31. An upper raceway or plate 32 engages the ball bearing rollers 33 and is connected through adapter 34 and draw bolt 36 with the piston 13a of motor 13. Cup shape housing 37 is threadably associated with the lower portion of bell housing 27 and contains a second centering member 38. Housing 37 is provided with downwardly extending boss 39 supporting upwardly extending yoke 41 forming part of the motor housing, bolt 42 serving to fasten the parts in assembled relation.

Bell lock 43 extends from the main machine housing 11 and protrudes radially inwardly through an orifice 44 in bell housing 27 functioning to lock the bell housing 37 and motor 13 against arcuate movement notwithstanding the arcuate indexing of the collet assembly.

Draw bolt 20 extending from the upper coupling portion 14 is threadably connected with the lower terminal of draw bar 46 the upper terminal of which is threadably connected with the lower end of the collet proper 51.

The collet assembly 12 includes collet proper 51 split coaxially at 52 and formed externally with a diverging cam surface 53 cooperating with a complementary cam surface 54 within the collet assembly housing 56. Collet adapter 58 includes an upper radial flange 59 supporting collet housing proper 56 and having the lower terminal por-

tion thereof engaged by anti-friction bearing 61 when the bell housing 27 is in raised position as will appear. Embracing collet adapter 58 is a supporting collar 62 provided with a radially extending guide flange 63 cooperating with a complementary guideway 64 formed on main housing frame 11. Functioning to effect limited lateral reciprocation of the collar and collet assembly there is provided a radially protruding connector 66 adapted to be driven by a cam 67 in proper correlation with the cutting tool and indexing operation, in a well known manner. Worm and gear assembly 68 is effective to accomplish the arcuate indexing in the usual manner.

Particular attention is drawn to the provision of shoulder or stop 71 carried by main housing 11 for the purpose of cooperating with the lower terminal portion of bell housing 27 in effecting the releasing movement of the collet 51. It will be seen that with the collet 51 being moved in the work clamping direction the bell housing 27 engages the anti-friction bearing 61 with the lower terminal portion of collet adapter tube 58 thus taking all of the reaction, none being transmitted to the guide 64 or frame 11. This leaves ample clearance between stop 71 and the lower terminal portion of bell housing 27 with the result that collet assembly 12 may be freely indexed arcuately as well as laterally reciprocated without conflict with the main housing 11 or with the relationship between guide flange 63 and guideway 64. Of particular importance is the fact that upon the operation of piston 13a to release collet 51 the lower terminal portion of bell housing 27 is brought into supporting contact with stop 71 and the reaction of the force required to release the collet 51 is thus taken by the main housing stop 71 instead of by guide flange 63 and guideway 64.

The lower portion of the motor housing 13 may contain the usual valve assembly having an inlet 70, outlet 72 and lever and latch assembly 73 for actuating the inlet and discharge valves. In the closed position of lever assembly 73 pressure is admitted to the upper side of piston 13a thus drawing collet 51 axially downwardly causing the same to grip to work piece. With the lever assembly 73 in the collet open position as indicated pressure is admitted to the underside of piston 13a causing reaction in motor 13 to move the assembly downward with the result that the bell housing is first brought into contact with the stop 71 for the purpose of taking the reaction and then the collet 51 is pushed axially outwardly for releasing the work piece. In the normal operating position of the machine with the work piece in gripped position within the collet the motor 13 and the flexible coupling portions 14, 16 are suspended from the collet assembly. Any limited misalignment that may occur either in operating the collet to grip the work piece, or under other circumstances, is amply provided for by the first flexible coupling portion 14 while the second coupling portion 16 provides for maintaining the motor against arcuate movement while arcuately indexing the collet assembly and work piece.

It will thus be made to appear that the power means for operating the collet is so suspended from and correlated thereto that all of the reactions of both opening and closing the collet are confined to the collet assembly flexible connecting means and power unit and none of these reactions is transmitted to the guideway 64 or guide flange 63. This is true since in effecting

the closing or gripping operation of the collet the longitudinal reaction is taken from the motor housing through cup housing 37, bell housing 27, anti-friction bearing 61 and collet tubular adapter 58 while on the other hand the reaction force involved in opening the collet is taken by stop shoulder 71 engaged by the lower terminal portion of bell housing 27 thus completely eliminating any effect upon the guide 64 and associated guide flange 63. This is very important since in precision work if this guide 64 and guide flange 63 were subject to the reactions of opening and closing the collet the wear incident thereto would soon render continued precision work impossible.

While the present invention has been disclosed in connection with a specific embodiment thereof, it is to be understood that this is by way of example only and that the scope of the present invention is to be determined by the appended claims.

We claim:

1. In a gear cutting machine including a gear holding and indexing collet assembly, a main frame having a guide thereon, means for arcuately indexing said collet assembly and means for effecting a limited lateral reciprocation of said collet assembly on said main frame guide in correlation with said indexing means; the combination therewith of power means suspended from said collet assembly for opening and closing said collet assembly comprising a fluid pressure responsive motor having a cylinder defining housing containing a reciprocable piston; means connecting said piston with the gripping portion of said collet including a first ball and socket coupling portion effective to provide for limited misalignment, a second rotary anti-friction coupling portion effective to permit arcuate indexing of said collet, means retaining said piston against arcuate movement during said indexing operation; an embracing housing assembly connecting said motor housing with said collet housing including a first tubular collet adapter and a bell housing adapter disposed therebelow, a stop shoulder on said frame in normally spaced relation to the lower terminal of said bell housing, the operation of said piston in the collet opening direction being effective to first bring said lower terminal portion of said bell housing into contact with said machine housing stop shoulder for the purpose of taking the thrust following which said collet is moved axially outwardly to open position, the reverse movement of said piston being effective to first move said bell housing in the opposite direction into axial engagement with said collet tubular adapter for taking the thrust incident to drawing said collet into gear gripping position.

2. In a work piece shaping machine including means defining a main frame having a lateral guide thereon; means defining a work holding assembly including a guidable portion adapted to be supported on and guided by said main frame guide, and means for effecting lateral reciprocation of said work holding assembly on said guide; means for arcuately indexing said assembly; the combination therewith of power means suspended from said assembly for operating the same to work engaging and disengaging position, said power means comprising a pressure fluid responsive motor including a movable cylinder and a reciprocable piston therein, said reciprocatory movement of the piston being adapted to open and close said work holding assembly, flex-

ible coupling means connecting said piston with said work holding assembly whereby to provide for limited misalignment resulting from said reciprocation and arcuate indexing, tubular and bell members connecting said motor and work assembly and adapted to be moved by said cylinder, said bell member having a portion adjacent said main frame, whereby movement of the piston to open said work holding assembly will move said bell member to abut said main frame portion thereby to take up thrust incident to the opening of the work holding assembly by said motor.

3. In a gear cutting machine including a main frame, a gear holding collet mounted in said frame and having means to both arcuately index said collet and laterally reciprocate the same, the combination therewith of power means for operating said collet, said power means comprising a pressure fluid responsive motor including a movable cylinder and a reciprocable piston therein, a two-part housing assembly connecting said cylinder and said collet reciprocating means and arranged with one member adjacent said main frame, whereby movement of said piston to open said collet will move said one member into abut-

ment with the main frame thereby to take up thrust incident to the opening of said collet by said piston, and means defining a flexible coupling connecting said piston with said collet, said flexible coupling means including a first portion having a draw bar assembly one terminal of which is connected with said collet, the other terminal being in the form of a ball, a socket receiving said ball providing for limited misalignment; a second flexible coupling portion connecting said socket with said piston, said last named flexible coupling portion including roller bearings and providing for relative turning movement between said first coupling portion and said piston during indexing of said collet.
